TRAFFIC SIGNALING SYSTEM

Leroy A. Clark, Miami, Fla., assignor to Mercury Timer Company, a corporation of Florida

Application April 7, 1939, Serial No. 266,637

2 Claims. (Cl. 177—337)

This invention relates to traffic signaling systems, and more particularly to a very simple and economical circuit making and breaking mechanism for controlling traffic lights and to a new arrangement of wiring by virtue of which the likelihood of getting the various lights wholly out of synchronism, or the likelihood of the short-circuiting of any of the lights under attempts of inexperienced persons to adjust the timing of the same, will be prevented.

One embodiment of the invention by virtue of which I accomplish the foregoing objects is illustrated in the accompanying drawings, wherein:

Figure 1 is a plan view of the timing mechanism of the invention;

Fig. 2 is a front elevation of said timing mechanism;

Fig. 3 is an end elevation of the timing mechanism;

Fig. 4 is a fragmentary view of one of the toothed disks hereinafter described;

Fig. 5 is an enlarged fragmentary sectional view through one of the rock shafts which carry the mercury switches;

Fig. 6 is a vertical sectional view upon line 6—6 of Fig. 5;

Fig. 7 is a diagrammatic view of the wiring;

Fig. 8 is a fragmentary sectional view of the two central disks of the timing mechanism, and

Fig. 9 is a fragmentary sectional view of the right-hand disk of the timing mechanism.

Like numerals designate corresponding parts throughout the several figures of the drawings.

The timing mechanism is supported upon any suitable base 5, carrying an upstanding wall 6, of Bakelite or other suitable insulating material. A synchronous motor 7, such as is commonly employed in the driving of electric clocks, drives through any suitable gearing, indicated at 8, to a main drive shaft 9. The motor serves to drive this shaft 9 at a uniform and determined rate of speed, as for example, one revolution per minute.

Shaft 9 is suitably supported in bearings 10. A sleeve 11 is mounted to turn with respect to shaft 9. This sleeve carries disks 12 and 13, said disks being fixed to the sleeve so that they are forced to turn together. The shaft 9 has a pair of disks 14 and 15 pinned or otherwise secured thereto, so that they are forced to turn with the shaft. Disk 13 carries a cam 16, and disk 14 carries a cam 17.

These cams act as the disks rotate to thrust in one direction or the other against balls 18 or 19, which have rolling mounting upon the ends of

stub shafts 20, 21. These stub shafts in turn are carried at the lower ends of the arms 22 of the crank of wishbone formation. The upper portion 23 of this crank is bound by a nut 24 upon an angular portion 25 of a rock shaft 26 (see Fig. 5). Shaft 26 in turn is mounted for oscillation in a sleeve 27.

This sleeve 27 is held in place in the wall 6 by nuts 28. A collar 29 is held in place upon shaft 26 by a nut 30. A block 31 has a lost motion connection with shaft 26 through the medium of a pin 32, which engages in an arcuate slot 33 of the block, said pin being carried by a disk 34, which is splined upon or otherwise held against turning with respect to rock shaft 26.

As the disks 13 and 14 rotate, the cams act to rock the shaft 26 first in one direction and then in the other. This causes the pin 32 to move block 31 to thereby tip the tube 35 of a master mercury switch, said tube being carried by an arm 36 which projects from the face of the block 31. The lost motion connection described permits the block to fall over quickly and to thereby secure a quick closing of the circuit when the block has been moved to past-center position by the action of the pin 32.

The structure illustrated in Fig. 5 is duplicated with respect to additional mercury switches 37 and 38, and the same reference characters have been applied. However, the rock shafts 26^a, 26^b of the mercury switches 37 and 38 do not carry wishbone crank arms but carry simple crank arms 39 and 40 which coact with cams 41 and 42 of the disks 12 and 15 respectively. Springs 43, 44 tend to move the crank arms 39 and 40 toward their coacting cams to bring anti-friction balls 45, 46 into engagement with said cams.

An important feature of the present invention, and one which I believe to be novel with me, resides in making the disks 12 and 13 to turn in unison with sleeve 11 and making the disks 14 and 15 to turn in unison with each other, and in further providing means whereby the unit comprising 11, 12 and 13 may be adjusted as a whole, circumferentially, with respect to the unit comprising the elements 9, 14 and 15, while in addition providing for means for adjusting the cams 41 and 42 over the faces of the disks 12 and 15, respectively.

The means by which this is accomplished is best illustrated in Figs. 8 and 9. Here it is shown that the disk 13 and its cam 16 carry a vertical pin 47. This pin may be moved upwardly through guides 48 against the tension of a spring 49 to lift a transverse pin 50, carried by pin 47, out of

engagement with the teeth 51 of disk 14. When this is done, the disks may be adjusted circumferentially with respect to each other to give any desired position of the cams 16 and 17 in relation to each other.

When the pin 58 is released, it drops into one of the notches between the teeth, and in Fig. 4, I have illustrated that the toothed disks may have their notches numbered with numerals "a" from one to sixty, indicative of seconds. The positioning of the cams 16 and 17 determines the time of change between the north and south red light and the east and west red light; while the positioning of the cams 41 and 42 upon the disks determines the period through which the amber light will show before the green light comes on.

The manner in which this is accomplished may easily be understood by referring to Fig. 7. In this figure, 52 indicates a conductor constituting a source of incoming current. The mercury switches that I employ, while being of a conventional type, differ from simple circuit closers in that they complete one circuit when tipped in one direction and complete another circuit when tipped in the other direction.

For example, when 35 is tipped to the right, a circuit is completed at b through the contact bar c of the mercury switch to conductor 53. This conductor is connected to the contact bar d of the mercury tube 33, but at a point ahead of said mercury tube 33, a conductor 54 connects 53 with the north and south red light 55. When the tube 35 is tipped in the opposite direction, a circuit is completed at e between contact bar c and a conductor 56 which leads to the contact bar f of mercury tube 37. However, at a point ahead of mercury tube 37, a conductor 57 leads from 56 to the east and west red light 58.

Thus it will be seen that the tube 35, which constitutes the master switch, controls the two red lights under the influence of the setting of the two complete units 12, 13 and 14, 15, and that this control of the red lights which determines the duration of the complete cycle of operation of the switch is independent of the period of dwell between the amber and green lights of the north-south, east-west sides of the signal, this duration being determined by the time of tipping of 37 and 33.

With tube 33 in the position illustrated in Fig. 7, a circuit is completed at g through conductor 59 to the east-west green light 60. With tube 33 tipped in the opposite direction, a circuit will be completed at h through a conductor 61 to the amber light 62 of the east-west side of the signal. In like manner, with the tube 37 tipped to the position illustrated in Fig. 7, a circuit is completed at i through a conductor 63 to the amber light 64 of the north-south side of the signal. When tube 37 is tipped in the opposite direction, a circuit will be completed at j through a conductor 65 to the green light 66 of the north-south side of the signal.

The adjusting means for the cams 41, 42 are very similar to those previously described with respect to Fig. 8. However, in this case (see Fig. 9), the guides 67 for the vertical pin 47^a are not carried by a disk but are carried by a wall 68, constituting a part of the cam, and a tail 69 of the cam is traversed by shaft 9 and held in place by a collar 70 on said shaft. Upward movement of pin 47^a is against the tension of a spring 71, and a transverse pin 72, carried

by pin 47^a, engages in any of the notches between the teeth of the disks 12, 15.

Thus, in the case of the disks 12 and 15, the cams are swung around the faces of the disks 5 to the desired position; while in the case of the structure of Fig. 8, the units 11, 12, 13 upon the one hand, are adjusted as a whole with respect to the unit 9, 14, 15 upon the other hand, and the pin 50 (Fig. 8) locks these units in adjusted position with respect to each other.

In Fig. 3 I have illustrated a feature which may be employed or may be omitted, since the remainder of the structure will operate with or without it. In this figure, I have illustrated 15 a disk 73, graduated as indicated at 74 after the manner of a clock dial and provided with sixty graduations. A pointer or hand 75 is carried by a pin 76, which projects from the end of the shaft 9, and thus the movement of the hand 20 is in unison with shaft 9.

This facilitates the work of the officer charged with synchronizing lights at different intersections, because with the second hand of his watch set in synchronism with the hand 75, he can, 25 if the disk 74 and hand 75 be exposed to view, drive along the street and at a glance determine just how much any given signal is out of synchronism with its fellows.

I am aware of the fact that it is quite old 30 in the art to provide circuit closers embodying a plurality of contact making and breaking members, and even to use tipping mercury switches in conjunction therewith. However, I do not know of any mechanism embodying such 35 extreme simplicity as that disclosed in this application or embodying the master switch controlling the relation of the north and south cycle with respect to the east and west cycle, while leaving such master switch wholly free of accidental short-circuiting or disagreement due to the effort of any person to adjust the auxiliary switches controlling the amber and green lights of the north and south side of the signal, upon the one hand, and the east and west side of the 40 signal upon the other. It will be very clear that nothing that an inexperienced person might do in endeavoring to adjust the relationship of the amber and green lights could bring about any disorganization of the main cycle of operation.

50 In those traffic signals having a plurality of switches all of equal value, one of which controls one red light, another of which controls the other red light, another of which controls one green light, another of which controls the other green light, another of which controls one amber, and another of which controls the other amber light, all of said switches being independently adjustable, it is very easy to get the various lights so mixed up that it is almost 55 impossible to straighten them out. In an endeavor to do so, the inexperienced person frequently connects two positives to the same light, resulting in short-circuiting the lights, burning them out, and bringing about confusion in traffic. 60 Nothing of this sort can happen with the signal of the present invention.

65 While the mechanism that I have devised for accomplishing the foregoing results, and which I have illustrated herein, has been found to be highly efficient in actual tests and is very economical of construction and certain in operation, I wish it to be understood that the invention is not limited to this particular mechanism.

70 It is clear that the skilled engineer may find other ways of utilizing the principles of the in-

vention through mechanism of another type. Therefore, it is to be understood that the invention includes within its purview whatever changes fairly come within either the terms or the spirit of the appended claims.

Having described my invention, what I claim is:

1. In a system of the character described, a group of east-west lights comprising a "stop," a "go" and a caution light, a group of north-south lights comprising a "stop," a "go" and a caution light, a master switch which when in one position closes a circuit energizing one stop light, and when in another position closes a circuit energizing the other stop light, said two circuits being independent of and including none of the "go" or "caution" lights, a pair of circuits for the east-west group in which the "caution" and "go" lights of said group are respectively included, a pair of circuits for the north-south group in which the "caution" and "go" lights of said group are respectively included, an auxiliary, two-position switch for each of said pairs of circuits, said switches in one position energizing its associated "caution" light, and in its other position energizing its associated "go" light, and means for supplying energizing current for said pairs of circuits to the auxiliary switches through and under control of the master switch.

2. In a system of the character described, a group of east-west lights comprising stop, caution, and go lights, a group of north-south lights comprising stop, caution, and go lights, a master switch, a pair of auxiliary switches, circuits including said switches and lights, a pair of uniformly moving units, means for adjusting said units bodily with respect to each other, a member carried by each of said units, one of which shifts the master switch to circuit completing position in one direction and the other of which shifts the master switch to circuit completing position in the other direction, the position of said members with respect to each other determining the time of shifting of the master switch, and a member carried by each of said units and adjustable as to position upon said unit and engaging and shifting the auxiliary switches respectively, to and from circuit-closing position, the said circuits including circuits controlled by the master switch and including no caution or go light which when energized illuminate the stop lights of the respective signals independently of the auxiliary switches, and additional circuits controlled by and including both the master switch and the auxiliary switches, which when energized illuminate either the go or caution lights of the signals according to the position to which the auxiliary switches have been shifted.

LEROY A. CLARK.
